UNITED STATES PATENT OFFICE.

FRANK R. HARTSOCK, OF WARSAW, INDIANA, ASSIGNOR OF ONE-THIRD TO CHARLES O. DICKEY AND ONE-THIRD TO LEONARD E. DICKEY, BOTH OF WARSAW, INDIANA.

WHEEL-PITCH GAUGE.

Application filed June 28, 1926. Serial No. 119,104.

As is well known, it is desirable to slightly incline the spindles of the vehicle axle downwardly and outwardly to thus cause the wheels to incline slightly upwardly and outwardly, this inclination being called the camber or pitch; and it is also well known that it is desirable to incline the spindles of the front, steering wheels of a motor vehicle slightly forwardly to cause the wheels to 10 slightly converge forwardly, this converging position being referred to in the trade as the "toe-in." It is the object of my invention to enable one to quickly and easily gauge the camber and "toe-in" or pitch of vehicle 15 wheels with a view of determining whether or not they are functioning properly, it being of the utmost importance to properly set the wheels in order to avoid undue wear of the pneumatic tires. It is the special 20 object of the present invention to adapt the gauge for convenient use on the modern cars which, as is well known, are provided with a number of parts adjacent the front 25 wheels that must be avoided in using a gauge of this class.

In the drawing—

Fig. 1 is a plan view of my improved apparatus partly broken away;

Figs. 2, 3 and 4 are detail views herein-after described.

My device consists, in its preferred form, of a pair of bars 5 overlapped upon each other and adapted to relatively slide, these two bars being held in their overlapped position by means of a pair of loops 6, one being rigidly attached to each of the bars. A retractile spring 7 is employed for normally tending to endwisely separate or extend the bars, this spring being arranged parallel to the bars and being connected at its opposite ends to the aforesaid loops 6.

Rigidly attached to each of the bars 5 near its outer end is a forwardly-extending arm 8, and pivotally mounted on the extreme forward end of this arm is a gauge-lever 9 whose forward end 10 is curved outwardly and whose rear end is sharpened to provide a pointer 11, which pointer works over a scale-plate 12 fastened on top of the bars 5 and 8 by rivets 13, over the joint between the bars 5 and 8.

A spring tends to swing the bent end 10 outwardly and the pointer inwardly, this spring consisting of a coil 14 surrounding the nut 15 on the pivot-bolt 16 connecting

the gauge-lever to the supporting arm 8; and this coil 14 has two oppositely-extending arms, one, 17, being engaged in a hole in the lever 9 at a point distant from the pivot-bolt 16, while the other arm, 18, engages in a hole in the arm 8 at a point distant from said pivot-bolt 16. The end of the arm 18 extends through the hole in the arm 8 and is bent to form a stop-finger 19 against which the pointer-end of the gauge-lever normally abuts, thus holding this gauge-lever in convenient position for applying to a wheel-felly.

In using the device, the two supporting bars 5 are slid inwardly on each other against the action of the spring 7, and the bar thus contracted is passed between the pair of wheels to be gauged; then the supporting bars are released to permit the spring 7 to normally slide the supporting bars outwardly until the ends of the supporting bars abut against the fellies of the respective wheels, the inner ends of the gauge-bars being allowed to rest against the wheel-fellies at a point beyond the centers of the wheels, as usual with this type of gauge and as shown in Fig. 3, the numeral 20 designating the wheel-felly. The relative inclination of the wheels will be indicated on the scale-plate. In gauging the camber or pitch of the wheels, the gauge-bars 5 are of course placed in an upright position against the inner faces of the wheels at a point in front of or in the rear of the axle; and, in gauging the "toe-in", 90 the gauge-bars are placed in a horizontal position at a point centrally below the axle.

By employing a spring to normally swing the gauging end of the gauge-bar outwardly as well as a spring to normally extend the supporting member 5—5, it will be seen that the apparatus adjusts itself to the wheels automatically when the bars 5—5 are released. The use of the actuating spring 14 and the stop 19 also insures the gauge member being held in proper position at all times for use, thereby leaving the hands of the operator free to manipulate the supporting bars. This construction also results in placing the scale-plate in the best possible position for quick and easy reading. This construction also is advantageous in that it may be readily used on cars having not only fenders but also four-wheel brake equipments, since the gauge may be 110

2
applied to the wheels at a considerable distance from the center thereof.

What I claim as new is:

1. In a wheel-pitch gauge, a supporting member embodying a pair of bars and means for slidably connecting said bars for parallel movement, means normally tending to extend them, each bar being provided with an arm near its outer end extending forwardly with respect to said supporting member, a scale-plate at the junction of each arm and its bar, a gauge-lever pivotally mounted on the forward end of each bar and having its forward end turned outwardly for engagement with the wheel-felly and having its rear end pointed and adapted to move over the adjacent scale, and a spring at the joint of each gauge-bar with its arm normally tending to swing the forward end of the gauge-bar outwardly, stops being employed to restrict this outward movement of said gauge-bars.
2. In a wheel-pitch gauge, a supporting member embodying a pair of bars and means for slidably connecting said bars for parallel movement, means normally tending to extend them to permit the outer ends thereof to rest against the opposite wheels, a

gauge-bar pivotally mounted on each of said bars and projecting forwardly therefrom, a scale-plate cooperating with the rear end of each of said gauge-bars, a spring for each gauge-bar normally tending to swing its forward end laterally, and a stop for restricting the action of this spring to thereby hold the gauge-bar in position for engagement with the wheel-fellies.

3. In a wheel-pitch gauge, a supporting member embodying a pair of overlapped bars and a spring normally tending to shift the bars endwisely apart, an arm attached to each gauge-bar near its outer end extending forwardly with respect to said supporting-member, a scale-plate adjacent to the rear end of each arm, a gauge-lever pivoted on the forward end of each arm and having its rear end pointed to serve as an indicator-finger for the scale-plate, a spring at the pivotal joint of each gauge-lever, said spring having one end connected to the gauge-lever and the other end to the arm, this latter end of the spring being extended to form a stop.

In testimony whereof I hereunto affix my signature.

FRANK R. HARTSOCK.
